[57] CLAIM

The ornamental design for a combined perfume bottle and closure, as shown and described.

DESCRIPTION

FIG. 1 is a right side elevation of a combined perfume bottle and closure showing my new design, the left side elevation is the same;

FIG. 2 is a front elevation thereof, the rear elevation is the same; and

FIG. 3 is a perspective view thereof.

The bottom of the perfume bottle is plain.

FIG. 3
